INKWELL

Filed Nov. 24, 1922

Fig. 1.

Fig. 2.

A cross-sectional view of a cylindrical component. The top surface features a central rectangular cutout with a textured pattern. The internal structure includes a central vertical column (10) with a horizontal slot (4) near the bottom. A horizontal rib (6) is positioned above the central column. The outer wall of the cylinder is marked with diagonal hatching. External features include a flange (1) with a circular cutout (13) on the right side, a stepped base (14) at the bottom, and a small circular protrusion (8) on the left side. The bottom edge of the cylinder is labeled with the number 5.

UNITED STATES PATENT OFFICE.

FREDRICK C. LUETHI, OF STOUGHTON, WISCONSIN, ASSIGNOR OF ONE-HALF TO
ARTHUR T. C. OLSEN, OF STOUGHTON, WISCONSIN.

INKWELL.

Application filed November 24, 1922. Serial No. 603,020.

To all whom it may concern:

Be it known that I, FREDRICK C. LUETHI, a citizen of the United States, residing at Stoughton, in the county of Dane and State 5 of Wisconsin, have invented new and useful Inkwells, of which the following is a specification.

This invention relates to ink wells, and more particularly to bases therefor.

10 The object of the invention is to provide a device of this character so constructed as to supply ink from a container to a plurality of dip cups located adjacent the container so that several persons may use the same 15 ink well simultaneously without conflict.

Another object is to provide the various dip cups with distinguishing means so that they may be readily located and which will also protect the edges of the cups as well as 20 the pen holder.

With the foregoing and other objects in view which will appear as the description proceeds, the invention resides in the combination and arrangement of parts and in 25 the details of construction hereinafter described and claimed, it being understood that changes in the precise embodiment of the invention herein disclosed may be made within the scope of what is claimed without 30 departing from the spirit of the invention.

In the accompanying drawings:—

Figure 1 represents a top plan view of an ink well embodying this invention.

Fig. 2 is a transverse section taken on line 35 2—2 of Fig. 1.

Fig. 3 is a similar view showing a slightly different form of the invention, and

Fig. 4 is a detail transverse section of a pen rack used in connection with the well.

40 In the embodiment illustrated in Figs. 1 and 2, a base 1 is shown which may be composed of any suitable material preferably of glass and which has an ink reservoir 2 centrally mounted thereon, said reservoir being 45 here shown provided with an aperture 3 in its bottom closed by a cork 4.

The base 1 is preferably provided on its lower face with rubber feet 5 which spaces it above the supporting surface and prevents 50 scratching of the surface by the well.

A plurality of dip cups 6 are arranged on the base 1, any desired number being employed, four being here shown and which

communicate with the central reservoir by conduits 7, the bottom of these cups being 55 arranged in a plane below the bottom of the reservoir so that the cups will retain ink after the reservoir has become empty.

Arranged around the upper edge of each dip cup 6 is a hard rubber ring 8 mortised to 60 fit within the cup as shown clearly in Fig. 2 and which may be of any desired color, black preferably. This hard rubber ring is set slanting as shown in Fig. 2, and the color 65 thereof being different from that of the base, renders it easy for the writer to locate the cup.

The base 10 is preferably provided at each corner with a plurality of upstanding nibs 70 9, four being here shown and which are designed to form pen racks.

In the form shown in Fig. 3, the dip cup 6' is located some distance from the reservoir 2 and is connected with it by a bridged conduit or passage 10, over which a removable cover 11 is mounted. By locating the cup 6' at a point remote from the reservoir, it may be disposed nearer the writer and consequently be more convenient.

The base 1 is provided with a groove 12 in its bottom near one side thereof with which a hook 13 carried by a pen rack or tray 14 is designed to be detachably engaged. This hook interlockingly engages with the base as shown in Fig. 3 and when the tray is 80 connected, holds it so as to present a unitary structure. It is of course understood that the tray 14 may be of any suitable or desired configuration, being either trough-shaped as shown in Fig. 3 or in the form of a rack 15 85 as shown in Fig. 4.

I claim:—

An ink well base having an ink reservoir mounted thereon and provided in its lower face with a recess, and a tray having an upstanding hook for interlocking engagement with said recess to hold the tray in operative position.

95 In testimony that I claim the foregoing as my own, I have hereto affixed my signature 100 in the presence of two witnesses.

FREDRICK C. LUETHI.
